UNITED STATES PATENT OFFICE

2,588,661

CURTAIN STRETCHER

Forest R. Ruby, Detroit, Mich.

Application August 26, 1946, Serial No. 693,133

1 Claim. (Cl. 45—24)

1

This invention relates to apparatus for stretching and drying fabrics, such for example, as curtains.

The invention has as its general object to provide fabric stretching apparatus composed of a frame having a relatively few simple parts capable of being economically manufactured, assembled and disassembled.

It is a more specific object of this invention to adjustably support end and side bars or rails on the frame in a manner which enables the user to readily alter the effective area of the frame to accommodate fabrics of many different sizes.

Another object of this invention is to provide apparatus wherein the fabric is readily attached by pins anchored in recesses formed in the front surfaces of the frame members and bars along one longitudinal edge thereof and having a length equal to or less than the depth of the recesses. Thus the pointed ends of the pins are shielded by the front surfaces of the frame members and are prevented from interfering with sliding movement of the bars relative to the frame members.

Still another object of this invention is to detachably and slidably secure the bars or rails to the frame members by brackets capable of being readily manipulated without the assistance of tools or other implements to attach and detach the adjacent rails or bars from their respective frame members.

A further object of this invention is to provide means on the respective brackets for latching the bars or rails in their selected adjusted positions relative to the frame members.

The foregoing as well as other objects will be made more apparent as this description proceeds, especially when considered in connection with the accompanying drawings, wherein:

Figure 1 is a front elevational view of stretching apparatus constructed in accordance with this invention;

Figure 2 is a fragmentary perspective view of a part of the apparatus shown in Figure 1;

Figure 3 is a fragmentary perspective view of another part of the apparatus;

Figure 4 is a side elevational view illustrating the supporting means provided on the apparatus;

Figure 5 is a sectional view taken on the line 5—5 of Figure 1;

Figure 6 is a sectional view taken substantially on the line 6—6 of Figure 1;

Figure 7 is a fragmentary front elevational view of one of the frame members;

Figure 8 is a side elevational view of the sup-

2

porting means showing the latter in a different position;

Figure 9 is a perspective view of the attaching bracket;

Figure 10 is a cross sectional view taken substantially on the line 10—10 of Figure 1;

Figure 11 is a rear fragmentary elevational view partly in section of the construction shown in Figure 3; and

10 Figure 12 is a fragmentary sectional view showing the means for removably securing one of the frame members and adjustable end bar of the apparatus.

The apparatus forming the subject matter of this invention is indicated in Figure 1 of the drawings by the reference character 15 and is for the purpose of supporting curtains or equivalent fabrics in a stretched condition during drying. As will be more fully hereinafter understood, the apparatus is adjustable to enable effectively stretching fabrics or curtains of various different sizes.

The apparatus 15 comprises a frame 16 having horizontal side frame members 17 and 18 and having vertical end frame members 19 and 20. In use the side frame member 17 forms the top of the frame and the frame member 18 forms the bottom of the frame. The extremities of the side frame members are respectively detachably connected to the ends of the vertical frame members by quickly detachably fastener elements 21, which may be in the form of bolts having the usual thumb nuts secured thereto at the rear side of the frame. In the present instance the frame

30 35 is held in its rectangular shape by a brace 22 having one end pivoted to the frame member 20 by a pin 23 and having the opposite end secured to the top frame member 17 by a fastener element 24. As shown in Figure 10 of the drawings, the fastener element 24 is similar to the fastener elements 21 in that it comprises a bolt 25 and a wing nut 26. Thus the brace 22 may be readily secured to and removed from the top frame member 17. The frame 16 is further braced by a vertical frame

40 45 50 bar 27 similar to the end frame members and having the opposite ends quickly detachably connected to the top and bottom frame members intermediate the ends of the latter by fastener elements 28, which may be the same as the fastener elements 24 previously described.

In use the frame may be supported in a substantially vertical position by means of a pair of foldable braces 29 attached to the end frame members 19 and 20 respectively. One of the braces is shown in Figures 4 and 8 of the draw-

ings and comprises a leg 30 pivoted at the upper end to a bracket 31 by means of a pin 32. The bracket 31 is secured to the rear side of one of the vertical end frame members adjacent the top of the latter, and the leg 30 is of sufficient length to support the frame 16 in a substantially vertical position on the ground or other supporting surface. The leg 30 is held in its frame supporting position by means of a link 32 having one end pivoted to the outer edge of one of the vertical frame members by a pin 33 and having a hook 34 at the free end for engaging over a headed pin 35 projecting from the adjacent side of the leg 30. The construction is such that the links 32 at opposite ends of the frame may be readily disengaged from their respective supporting legs 30 to permit the latter to be swung to the broken line position shown in Figure 4. In this broken line or inoperative position of the legs 30, the latter lie immediately adjacent the rear surfaces of the vertical end frame members and are held in this inoperative position by the links 32. As shown particularly in Figure 8 of the drawings, the links 32 are formed with slots 36 intermediate the ends thereof, and the slots are open at the bottom edge of the links to enable the headed pins 35 to enter the slots. Thus the legs 30 are held in their inoperative positions immediately adjacent the rear sides of the vertical end frame members when not in use.

Supported on the frame 16 for vertical sliding movement between the top and bottom frame members is a side bar 37. The side bar 37 is formed of two sections secured together in end-to-end relationship by a bracket 38' and having a combined length approximating the length of the top and bottom frame members. The adjustable side bar 37 is slidably supported on each of the vertical members 19, 20 and 27 by a bracket 38. Inasmuch as all three brackets are identical in construction, the following description will be confined to the bracket associated with the vertical end frame member 19. As shown in the several figures of the drawings, the bracket 38 comprises a base portion 39, having flanges 40 projecting laterally from opposite side edges and spaced sufficiently from each other to slidably receive therebetween the vertical end frame member 19. The base portion 39 is formed with a pair of lugs 41 apertured to receive fastener elements 42 for securing the bracket to the slidable side bar 37.

The bracket 38 is held in assembled relation with the vertical frame member 19 by means of a substantially U-shaped spring wire clip 42 having the base portion 43 hinged to the free edge of one of the flanges 40 and having the leg portions 44 extending toward the other flange 40 across the rear face of the vertical frame member 16. As shown particularly in Figure 5 of the drawings, the free edge portion of the latter flange 40 is formed with a slot 45 having an entrant opening 46 for the reception of the leg portions 44. The normal distance between the free ends of the leg portions 44 is substantially greater than the length of the slot 45, requiring the leg portions to be pressed together in order to enable the same to be inserted through the opening 46 into the slot 45. As soon as the leg portions are released, the same engage opposite end walls of the slot 45 and are held under tension against these walls. Thus the clips serve to slidably secure the bracket on the vertical end frame member 19. If desired, suitable recesses 48 may be provided at opposite ends of the slot 45 for re-

spectively receiving the free end portions of the legs 44 and thereby prevent accidental disengagement of the leg portions from the slot.

As shown in Figure 9 of the drawings, a lug 49 is struck outwardly from each of the flanges 40 on the bracket and are bent to project laterally from the base 39 in a direction opposite the direction of the flanges 40. The lugs are formed with aligned openings 50 and a shaft 51 is rotatably supported by the lugs 49. The shaft 51 extends for substantially the full length of the slide bar 37 and comprises two aligned sections 52 and 53. The adjacent ends of the sections are polygonally shaped in cross section and are joined together by a coupling 54 of corresponding cross sectional area. The coupling 54 is shown in Figure 11 as pinned to the inner end of the shaft section 53 and as telescopically engaging the adjacent end of the shaft section 52. The shaft 51 is supported intermediate the ends from the bracket 38' by means of a hanger 55 having a flange 56 secured to the bracket 38' and having a flange 57 apertured for receiving the shaft section 53. As shown in Figure 11 of the drawings, the flange 55 is positioned adjacent the coupling 54 for engagement by the latter to prevent shifting movement of the shaft 51 in one direction relative to the slide bar 37. In this connection it will be noted that the bracket 38' is fixed to the inner end of one section of the bar 37 by fasteners 54' and is detachably secured to the adjacent end of the other section of the bar 37 by means of fastener elements having bolts 58 and wing nuts 59. The above arrangement is such that the slide bar 37 and the shaft 51 may be removed in sections when dismantling the apparatus.

Secured to the shaft 51 opposite the base portion 39 of each bracket 38 is a pinion 60. The pinions 60 project through slots 61 formed in the base portion 39 of the brackets and respectively mesh with racks 62. The racks 62 are respectively secured in grooves 63 formed in the front faces of the vertical members 19, 20 and 27. The grooves 62 and accordingly the racks extend for substantially the full length of the members 19, 20 and 27. As shown particularly in Figure 5 of the drawings, the racks 62 are in the form of a corrugated strip of metal and the pinions 60 mesh with the corrugations, so that rotation of the shaft 51 in opposite directions alternately moves the slide bar 37 upwardly and downwardly. The shaft is rotated by a crank 64 formed integral with the end of the shaft adjacent the frame member 19.

It follows from the foregoing that the slide bar 37 may be adjusted within close limits to preselected positions and provision is made herein for securing the slide bar 37 in any one of its numerous adjusted positions. As shown in Figure 6 of the drawings, a channel-shaped finger 65 is pivoted at one end to the slide bar 37 adjacent the vertical end frame member 19 by one of the fastener elements 42 previously described as securing the adjacent bracket 38 to the slide bar. The finger 65 is formed with an elongated slot 66 in the base portion thereof, and the shaft 51 projects through this slot. A nut 67 is secured to the shaft 51 and is adapted to be received in the slot 66 upon swinging movement of the finger 65 to its operative position. When in the latter position, the opposite side walls of the slot engage the adjacent opposite sides of the nut 67 and thereby prevent rotation of the shaft 51.

or, in other words, secures the slide bar 37 in its selected position.

Cooperating with the side slide bar 37 is a vertical end slide bar 70 having a length approximating the length of the end frame members 19 and 20. The bar 70 is slidably supported at its opposite ends on the top and bottom frame members between the end frame member 19 and the vertical frame bar 21. The slideable connection between the opposite ends of the bar 70 and the top and bottom frame members is effected by brackets identical to the brackets 38. Therefore, the above detail description of the brackets 38 will suffice for the brackets associated with the slide bar 70, and corresponding parts of these brackets are indicated by the same reference characters. It will suffice to point out that the slide bar 70 is moved lengthwise of the top and bottom frame members by a shaft 71 journalled in the lugs 49 of the brackets 38 and having a crank 72 at one end thereof to enable readily rotating the same. A pair of pinions 73 are secured to the shaft 71, and these pinions respectively mesh with racks 74 in the form of corrugated strips similar to the strips 62. The racks 74 are, in turn, respectively secured in grooves 75 formed in the rear sides of the top and bottom frame members 17 and 18. Thus the slideable end bar 70 cooperates with the slideable side bar 37 to define areas within the frame 16 of different sizes determined in dependence upon the size of the curtain for fabric to be accommodated. The slideable end bar 70 is held in any one of its various adjusted positions in the same manner previously described in connection with the adjustable bar 37. As shown in Figure 12 of the drawings, a channel-shaped finger 76 is pivoted to the upper end of the bar 70 and is formed with an elongated slot 77 in the base portion thereof for receiving the polygonally shaped nut 78 on the shaft 71. When the finger 76 is in its full line position shown in Figure 12, the nut 78 is received in the slot 77 and rotation of the shaft 71 is prevented. However, when the finger 76 is swung to its broken line position shown in Figure 12 of the drawings, the opposite sides of the slot 77 are disengaged from the nut 78 and rotation of the shaft is permitted.

It will be noted from the several figures of the drawings that each of the frame members and slide bars is formed with a recess 80 in the front face thereof. The recesses 80 extend for substantially the full length of the frame mem-

bers and side bars and pins 81 are secured to the base portions of the recesses. The pins are spaced from each other longitudinally of the recesses and the length of the pins does not exceed the depth of the recesses. Thus the pointed ends of the pins on the frame members are prevented from interfering with the adjustable bars. It will also be noted from Figure 1 of the drawings that each of the frame members and slide bars may be calibrated in inches if desired to assist the user in stretching the fabrics or curtains to the required size.

What I claim as my invention is:

Apparatus for stretching fabrics comprising
 15 pairs of side and end members secured together at their extremities to form a frame with the members of one pair overlapping those of the other, said members having longitudinal grooves therein with the grooves of the rear pair in the front faces thereof and those of the front pair in their rear faces, a rack secured within the grooves of each member and extending for substantially the full length of the latter, a side bar extending transversely of the end frame members and slidably supported thereon, a shaft rotatably supported on the side bar and extending lengthwise of the latter, pinions secured to said shaft and respectively meshing with the teeth of the racks secured to the end frame members, an
 20 end bar extending at right angles to the side bar and supported on the side frame members for sliding movement lengthwise of the latter, a shaft rotatably supported on the end bar and extending longitudinally of the latter, and a pair
 25 of pinions fixed on the second shaft respectively meshing with the teeth of the racks secured to the side frame members.
